(57) **CLAIM**

The ornamental design for a digital signage, as shown and described.

DESCRIPTION

FIG. 1 is a front top perspective view of a digital signage showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear top perspective view thereof;

FIG. 9 is an enlarged view of the encircled portion 9 in FIG. 2;

FIG. 10 is an enlarged view of the encircled portion 10 in FIG. 5;

FIG. 11 is an enlarged view of the encircled portion 11 in FIG. 6;

FIG. 12 is an enlarged view of the encircled portion 12 in FIG. 8;

FIG. 13 is an enlarged view of the encircled portion 13 in FIG. 8; and,

FIG. 14 is an enlarged view of the encircled portion 14 in FIG. 8.

The dashed broken lines in the drawings illustrate portions of the digital signage that form no part of the claimed design. The dot-dot-dash broken lines in the drawings encircling portions of the claimed design that are illustrated in enlargements form no part of the claimed design.

1 Claim, 14 Drawing Sheets
